UNITED STATES PATENT OFFICE.

AXEL LEVEDAHL, OF AURORA, ILLINOIS, ASSIGNOR TO INDEPENDENT PNEUMATIC TOOL COMPANY, OF CHICAGO, ILLINOIS, A CORPORATION OF DELAWARE.

PNEUMATIC TOOL.

Application filed July 30, 1919. Serial No. 314,373.

To all whom it may concern:

Be it known that I, AXEL LEVEDAHL, a citizen of the United States, residing at Aurora, in the county of Kane and State 5 of Illinois, have invented new and useful Improvements in Pneumatic Tools, of which the following is a specification.

This invention relates to improvements in pneumatic tools and consists of the matters hereinafter described and more particularly pointed out in the appended claims. The invention is herein illustrated and described as embodied in a pneumatic tool of the kind known as a sand rammer of 10 the bench type; that is to say, of the type wherein the tool has a relatively short length, so that it may be readily grasped by both hands of an operator and held in a substantially upright position for packing 15 or tamping sand about a pattern in a molder's flask when placed on a bench or other raised support above the floor of the workroom.

The object of my invention is to improve 20 the construction of pneumatic tools used for such purpose, and this object as well as others will be made more apparent as I proceed with my specification.

In the drawings—

Figure 1 is a side elevational view of a 25 sand rammer embodying the features of my invention;

Figures 2 and 3 illustrate, collectively, a 30 longitudinal sectional view through the rammer, and on a scale somewhat larger than that shown in Fig. 1;

Figures 4 and 5 are transverse sectional 35 views taken on lines 4—4 and 5—5, respectively, of Fig. 1;

Figures 6 and 7 are top plan views of the 40 locking mechanism and showing the pawl thereof in both its locking and unlocking positions;

Figure 8 is a transverse sectional view 45 taken on line 8—8 of Fig. 6; and

Figure 9 is a top plan view, with parts 50 broken away to show a detail of construction to be hereinafter described.

A sand rammer embodying the features 55 of my invention comprises a hollow barrel 1, as customary in pneumatic tools, and within which is reciprocated a piston 2 made hollow, as shown in Figs. 2 and 3, for the purpose of reducing the weight of such part. The piston 2 is provided at one end

with a rod 3 projecting outward from the barrel through the lower end thereof and having secured thereto a stamper or peen 4. The form of stamper 4 shown in the drawings is provided with a rectangular stamping face 5 so that the corners of a rectangular mold or flask may be reached. Should the flash be circular, a circular stamper may then be applied to the end of the piston rod 3. To prevent rotation of the piston rod, which would be required when a square stamper 4 is used, I provide the piston rod with one or more concave flutes 6 extending lengthwise thereof and into which extend like shaped keys (not shown) on the locking 60 ring 7 of the stuffing box provided at the lower end of the barrel and through which the piston rod extends. The stuffing box structure is the same as that shown and described in my copending application filed 65 July 30, 1919, and having Serial Number 314,374. As in such structure, the ring 7 is provided with a key to engage in a keyway or groove 8 formed in the lower end of the barrel to hold the parts from rotation 70 in the reciprocating of the piston rod 3. The opposite or upper end of the barrel is enlarged, as at 9, to receive a valve block 75 10, in which reciprocates a valve member 11 having differential pressure areas, a feature 80 well known in the pneumatic tool art. Said valve member 11 serves to control the admittance and exhaust of motive fluid to and from the opposite ends of the barrel for the purpose of reciprocating the piston there- 85 in, this feature also being well known in this art. The enlarged upper end 9 of the barrel is left open to permit a throttle head 12 to be attached thereto and forms a rearward extension of the barrel, as shown in Figs. 1 90 and 3. Said throttle head 12 is provided with a cylindric extension 13 inserted into the open end of the enlargement 9, the extension 13 having an external screw thread 95 to engage an internal screw thread in the open end of said enlargement 9, as shown in Fig. 3. In this manner, the throttle head 12 is connected with the upper end of the barrel 1. Said throttle head is provided with an inlet passage 14 having at its outer 100 end screw threads to permit the attachment thereto of an air supply hose. Formed in the head 12, to the rear of the extension 13 and crossing the inlet passage 14 at substan- 105 tially right-angles thereto, is a circular bore 110

15 opening at its ends through the head 12 on opposite sides thereof. Fixed in said bore 15 is a valve housing 16 having ports 17, 18 on opposite sides of a valve seat 19 for permitting the passage of motive fluid through the valve housing when the valve member 20 is in open position, as shown in Fig. 3. Said valve member 20 is in the form of a ball and when in closed position seats against the under side of the valve seat 19. Said ball valve is normally held in closed position against its seat 19 by a coil spring 21 beneath the valve. Said spring rests against a screw plug 22 closing the lower end of the 15 valve housing or bushing 16. Slidably mounted in the housing 16, above the ball valve 20, is a valve stem 23 resting at its lower end on the ball valve and having its upper end extending beyond the like end of the housing 16, and over both of which is placed a dust cap 24, cup-shaped and having an inwardly extending annular wall 25 extending downward over the upper end of the valve housing 16, as shown in Fig. 3. 20 For opening the ball valve 20, I provide a hand lever 26 located on the outside of the tool and having at its rear end laterally spaced ears 27 engaging over the sides of the throttle head 12 and secured thereto by a pivot pin 28. The lever 26 extends along the barrel 1 toward its lower end and to a point beyond the enlargement 9, as shown in the drawings, and is curved transversely to conform to the curvature of the barrel 1 and its enlargement 9 so that when the lever is in position holding the valve 20 fully opened, as shown in Fig. 3, the lever will lie against the barrel and have no part thereof projecting beyond the same to strike exterior 25 objects in the handling of the tool during the operation thereof. The forward end 29 of the lever is offset toward the barrel so that such end will engage over the barrel beyond the shoulder 30 formed at the junction of the barrel 1 with its enlargement 9. The barrel 1 is provided between its ends and adjacent the enlargement 9, but beyond the forward end of the lever 26, with an annular, outwardly projecting rib 31, so positioned as to prevent the hand of the operator grasping the barrel and holding the lever in open position from sliding down the barrel and off the end of the lever. By the provision of the dust cap 24 and having the same slide over the adjacent end of the valve housing 16, sand, dirt, and dust are prevented from entering the valve housing 16 at such point, and thus the valve stem is prevented from being injured or damaged and from an accumulation of sand and dirt between such parts. The lever 26 extends over the dust cap 24 and is provided with an outwardly curved portion 32 to conform to the curvature at the top of the dust cap, and thus provides a suitable connection between

the valve stem 23 and the lever 26, so that the swinging movement of the lever is converted into a straight reciprocating action between the dust cap and the valve stem, thereby allowing the valve to be arranged at right-angles to the passage of the air to the block 10, and also eliminates wear on the parts. Moreover, the construction described permits the use of a one-pieced throttle lever and conforms to the shape of the handle of the tool and makes an easy grip for the hand of the operator, as is apparent.

The exhausts from the various ports and passages of the tool empty into an annular space 33 about the valve block 10, as shown in Fig. 3, and said space 33 communicates at its rear end with five ports 34, 35, as clearly shown in Fig. 5. The port 34 is made larger than any one of the ports 35 and communicates with the upper end of the bore 15 around the reduced end of the valve housing 16 at the dust cap 24 and reaches the atmosphere through a cluster of ports 36, 36 in the portion 30 of the throttle lever 26 in contact with the dust cap, as shown in Figs. 3 and 9. The sets of ports 35 on opposite sides of the port 34 communicate with passages 37 formed in the throttle head 12 on opposite sides of the bore 15, in which the valve housing 16 is located. Said passages 37 open outward through the throttle head beneath the throttle lever 26 and reach the atmosphere through ports 38, 38 in said throttle lever and on opposite sides of the cluster of ports 36, as shown in Fig. 9.

To lock the throttle head 12 on the barrel 1 and prevent the same from being unscrewed by the jarring of the tool while in use or otherwise, the upper end of the barrel is provided with a plurality of ratchet teeth 39 covering the entire end of the barrel, as shown in Fig. 5. In the throttle head is a locking pawl 40 slidably mounted in a dovetailed slot 41 closed at its inner end and opening at its outer end through the adjacent end of the throttle head 12, so that the pawl may project beyond the open end of the slot and engage the ratchet teeth 39 on the barrel 1, as shown in Figs. 1 and 6. The pawl 40 is shaped to fit and slide endwise in the slot 41, so that the pawl will not drop out of the slot through the open upper side thereof. For projecting the pawl 40 forward against the ratchet teeth 39, I provide a spiral spring 42, its inner end entering a recess 43 beyond the inner end of the slot 41 and opening into the same, and the other end of the spring extending into an aligned recess 44 in the pawl 40. The spring serves to force the pawl toward the barrel 1 and permits the pawl to ratchet over the teeth 39 as the throttle head 12 is screwed on the end of the barrel, the face of the teeth 39 and those 45 on the pawl being complementary but arranged to permit the pawl to

ratchet over the same in the screwing up of the head 12 on the barrel. Said teeth, however, are formed to prevent a reverse movement of the parts, and therefore when the 5 pawl engages the teeth 39, relative rotation of the head 12 and the barrel 1 in a direction to unscrew such parts will be prevented. In order to permit the head 12 to be unscrewed from the barrel, when that is desired, a suitable pointed implement or hand tool (not shown) is inserted into a notch 45^a in one side of the pawl, whereupon the pawl is retracted until said notch is brought into register with a notch 46 in the head 12 10 adjacent the rear end of the slot 41. When the parts occupy such position, the pawl is disengaged from the teeth 39, and to prevent the spring 42 from projecting the pawl forward, a piece of metal 47 is inserted into 15 the registering notches 45^a, 46 to make the pawl ineffective while unscrewing the head 12 from the end of the barrel. The pawl 40 has a plurality of teeth, as shown, and the head 12 at one side of the slot 41 is provided 20 with a lug 48, which extends into a groove 49 in one side of the pawl and in the path of a shoulder 50 at the rear end of said groove to prevent the pawl from slipping out of the slot 41 when the head 12 is dis- 25 sembed from the barrel.

In use, the operator grasps the barrel 1 with both hands, one above the other, and raises the tool into position to pack or stamp sand about a pattern in a mold or flask when 30 on a bench or elevated support. The length and weight of the tool are such that this may be readily and easily done. When the tool is raised to the position desired with its stamper 4 on the sand in the flask or mold, the operator with his upper hand grasps the throttle lever 26 and draws it into contact with the barrel, thereupon opening the ball valve 20 and permitting live air 35 to be supplied to the working parts of the tool. The transverse curvature of the lever 26 being the same as the barrel, permits the lever to lie along and in contact with the barrel so that the hand of the operator grasping the lever may be also used to grasp 40 the barrel at the lever in a natural and easy manner. In the vibration of the tool, the upper hand of the operator may slide down the barrel, but it is prevented from sliding off the free end of the lever 26 by contact 45 with the annular rib 31. This forms a support for the hand of the operator, and he need only use such force in grasping the tool as is necessary to hold the valve 20 open 50 against the tension of the spring 21 and maintain the tool in a substantially upright position required during the operation thereof. When it is desired to stop the operation of the tool, the operator releases the lever 26 and, by the action of the spring 21, the 55 valve 20 is closed, with the lever remaining

in a position to be grasped readily again for supplying motive fluid to the tool for operating it.

The construction described and shown possesses many advantages, which are as follows: The throttle valve mechanism is contained in a compact form in a throttle head, which may be readily connected with the upper end of the barrel 1 and will not project to any great extent beyond the end of the barrel to increase materially the length of the tool. The length of the tool is reduced to the minimum and permits it to be used effectively in packing sand in a mold or flask on a bench or other elevated support. The throttle lever 26 lies along and in contact with the barrel when holding the valve in open position and therefore may be readily grasped by the hand of the operator and permit him to have all his fingers around the barrel of the tool at the same time, and thus avoid the use of any one of his fingers of that hand to extend beyond the barrel for grasping the throttle lever. Moreover, the throttle lever is in one piece and therefore has no parts projecting beyond the barrel for holding the valve in open position. The dust cap 24 permits the swinging movement of the throttle lever to be converted into a straight reciprocating motion with the valve stem, and prevents sand, dirt, and dust from entering between the valve housing or bushing 16 and the valve stem, thus saving wear on such parts. The locking device between the throttle head and the barrel is positive and will lock the head against accidental movement or being jarred loose from strains and shocks to which the parts are likely to be subjected in the use of the tool. Other and further advantages of my invention will be apparent to those skilled in the art to which it relates.

While I have shown and described in detail a sand rammer constructed in accordance with my invention, yet it is of course to be understood that the several details of construction and arrangement of parts shown may be variously changed and modified without departing from the spirit and scope of my invention.

I claim as my invention:

1. In a pneumatic tool, the combination of a barrel, a throttle head secured to the rear end thereof and having a live air passage and an exhaust port, a self closing throttle valve for said passage, and a valve opening lever pivoted on said head at the rear of said valve and extending over the valve toward the forward end of said barrel, said lever having engagement between its ends with said valve for opening said valve upon the movement of said lever toward said barrel, said lever being curved transversely to conform to the curvature of said barrel and

provided in its portion extending over said valve with an exhaust port in communication with the exhaust port in said head.

2. In a pneumatic tool, the combination of a barrel, a throttle head secured to the rear end of said barrel and having a live air passage and an exhaust port, said throttle head having a bore extending across said passage and communicating with said exhaust port, a bushing in said bore and having a valve seat communicating on opposite sides with said passage, a valve member in said bushing and having a stem extending through one end thereof, and a valve opening lever pivoted to said head at the rear side of said valve and extending over the valve toward the forward end of said barrel, said lever having engagement between its ends with said valve stem for opening said valve upon the movement of said lever toward said barrel, said lever being provided in its portion extending over said valve with an exhaust port in communication with said bore.

3. In a pneumatic tool, the combination of a barrel, a throttle head secured to the rear end of said barrel and having a live air passage and a bore extending across said passage, a bushing in said bore and having a valve seat communicating on opposite sides with said passage, a valve member in said bushing and having a stem extending through the open end thereof, a dust cap applied over said stem and adjacent end of said bushing and having sliding engagement therewith, a valve

opening lever pivoted to said head at the rear side of said valve and extending over the valve toward the forward end of said barrel, said lever having engagement between its ends with said dust cap for opening said valve upon the movement of said lever toward said barrel, and a spring for normally holding said valve member against its seat and said dust cap against said lever.

4. In a pneumatic tool, the combination of a barrel, a throttle head secured to the rear end of said barrel and having a live air passage and a plurality of exhaust ports, said head having a bore extending across said passage and communicating with one of said exhaust ports, a bushing in said bore and having a valve seat communicating on opposite sides with said passage, a valve member in said bushing and having a stem extending through one end thereof, a valve opening lever pivoted to said head at the rear side of said valve and extending over the valve toward the forward end of said barrel, said lever having engagement between its ends with said stem for opening said valve upon the movement of said lever toward said barrel, said lever being provided with two sets of exhaust ports, one set communicating with the exhaust port opening into said bore and the other set communicating with the other of said exhaust ports in said throttle head.

In testimony that I claim the foregoing as my invention, I affix my signature, this 26 day of July, A. D. 1919.

AXEL LEVEDAHL.
